LOGROLLING GAME DEVICE

Hans Gabriel Jackson, Birchwood, Wis.

Application December 5, 1939, Serial No. 307,671

2 Claims. (Cl. 272—69)

My invention relates to apparatus enabling indulgence in the sport known as "log-rolling" under simulated conditions, and the primary object of the invention is to provide a simple, efficient and practical arrangement of this character whereby the sport mentioned may be carried on regardless of the time, the place, and weather conditions.

Other important objects and advantages of my invention will be apparent from the reading of the following description taken in connection with the drawings, wherein for purposes of illustration I have shown a preferred embodiment of my invention.

In the drawings:

Figure 1 is a general side elevational view, partly broken away and contracted, showing a preferred embodiment of my invention.

Figure 2 is a top plan view thereof.

Figure 3 is an enlarged fragmentary vertical longitudinal sectional view taken through one of the bearing assemblies.

Figure 4 is a transverse vertical sectional view taken through Figure 1 approximately on the line 4—4 and looking toward the left in the direction of the arrows.

Figure 5 is a transverse vertical sectional view taken through Figure 1 approximately on the line 5—5 and looking toward the left in the direction of the arrows.

Referring in detail to the drawings, the numeral 5 generally designates a log of suitable diameter and length, which may, according to the choice of the operator, be a finished or an unfinished log, the same having substantially squared ends 6 and 7 to which respective bearing assemblies 8 and 9 are secured by means of bolts 10. Each of the bearing assemblies comprises a hollow cylindrical shell 11 which has two interior annuli 12 and 13, the annulus 12 being located near the middle of the shell 11 with the annulus 13 between it and the right hand end of the shell as illustrated in Figure 3 of the drawings. The right hand end of the shell is axially threaded as indicated by the numeral 14 to receive a cap 15 while the opposite end of the shell is exteriorly threaded as indicated by the numeral 16 to receive a packing compressing cap 17, the latter being provided with an opening 18 through which the stub shaft 19 revolvably extends. The stub shaft 19 extends also through several layers of suitable packing 20 pressed in the end of the shell 11 against a washer 21 which works against a ball-bearing 22 whose opposite side abuts the laterally outward side of the an-

nulus 12. The stub shaft 19 has an enlarged portion 23 which turns in the bearing 22 and an annular enlargement 24 which bears against the laterally inward side of the bearing. The stub shaft 19 has a second annular enlargement 25 which bears against the longitudinally inward side of the ball-bearing 26 which is seated in the right hand end of the shell 11 and itself abuts the longitudinally outward side of the annulus 13. The bearing 26 receives an enlarged diameter portion 27 of the stub shaft 19 and the right hand end of the shaft is threaded as indicated by the numeral 28 to receive the tightening nut 29 which bears against a washer 30 which, in turn, bears against the longitudinally outward face of the bearing 26. At circumferentially spaced intervals the outside of the shell 11 has attached thereto generally L-shaped brackets 31, these brackets being fastened to the shell along the part which lies between and in the neighborhood of the annuli 12 and 13 as illustrated in Figure 3, and the right angularly related foot portions 32 are pierced with bolt-receiving holes 33 through which the bolts 10 pass into the log 5. The left hand extremity of the shaft 19 is threaded for a considerable distance as indicated by the numeral 34 and provided thereon with two spaced nuts 35 and 36 for engaging the opposite sides of the vertical member 37 of the respective one of the two supports or landing stages 38 and 39, between which the log 5 is by the means described revolvably supported. It is obvious that by adjusting the positions of the nuts 35 and 36 along the threaded portion 34 of the shaft 19 that logs of slightly different lengths may be readily accommodated.

Each of the landing stages comprises a heavy horizontal bolster 40 notched to receive the heavy vertical member 37 flush with the laterally inward edge thereof as indicated by the numeral 41 in Figure 4. The lower end of the vertical member 37 rests on the ground or other support (not shown) and at its inner side there is attached at the same level a cross member or foot 42, which like the bolster 40 extends at equal distances on opposite sides of the vertical member 37. Attached to the top of the vertical member 37 and similarly extending equally on opposite sides thereof is the platform 43 which extends laterally outwardly to seat in notches 44 in the upper ends of the angulated stiles 45 of the step-ladder or stairs 46, the steps being constituted by horizontal cross members 47 extending between the stiles. Upper and lower V-shaped brackets 48 and 49 are secured to the

inner edges of the stiles and to the adjacent edge of the bolster 40 while reinforcing blocks 50 are secured in place to take up the space between the stiles and the vertical member 37 and the platform 43 to provide a thoroughly braced structure.

Longitudinal spacer bars 51 and 52, disposed longitudinally at the opposite sides of the log 5 and somewhat above the bottom edge of the log, extend between the respective ends of the feet 42 and at the point of passing through these feet have respective nuts 53 and 54 threaded thereon to engage opposite sides of the feet to properly space and connect them and brace the stages 38 and 39 relative to the log 5, the manner of mounting the log revolvably also contributing to the rigidity of the structure as a whole, as will be evident.

Although I have shown and described herein a preferred embodiment of my invention, it is to be definitely understood that I do not desire to limit the application of my invention thereto except as may be required by the scope of the subjoined claims.

Having described the invention, what is claimed as new is:

1. A device of the character described comprising a pair of vertical supports, said supports

being horizontally spaced apart at a substantially greater distance than the length of a log to be rolled, horizontal stub shafts secured to and projecting from the facing sides of said vertical supports, said stub shafts being of relatively small diameter and being in axial alignment, elements rotatably mounted on the free ends of said stub shafts, a relatively large diameter log positioned between said vertical supports and having its opposite ends substantially spaced from the said supports, means fixedly connecting said elements to the ends of said log in substantial alignment with the axis of the log, and spacing means extending between said supports on opposite sides of said log, said spacing means being connected to space said vertical supports and brace the same in position.

2. In a log-rolling game device, a pair of opposed supports, stub shafts mounted on said supports, said stub shafts being in axial alignment; a log rotatably supported by said stub shafts, tubular elements secured to the respective opposite ends of said log and extending longitudinally therefrom, said tubular elements being sleeved on said stub shafts, and bearing assemblies housed within said tubular elements and disposed circumjacent the respective stub shafts.

HANS GABRIEL JACKSON.
